UNITED STATES PATENT OFFICE

JACOB BENTZ, OF BROOKLYN, NEW YORK.

IMPROVED MACHINE FOR FRAMING MATCHES.

Specification forming part of Letters Patent No. **55,808**, dated June 26, 1866.

To all whom it may concern:

Be it known that I, JACOB BENTZ, of Brooklyn, Eastern District, Kings county, State of New York, have invented certain new and useful Improvements in Machinery for Framing Match-Splints for Dipping; and I do hereby declare that the following is a full and correct description thereof, reference being had to the accompanying drawings, and to the letters of reference thereon.

Figure 1 of the drawings is a plan view of the machine; Fig. 2, section through red line *xx* of Fig. 1; Fig. 3, section through red line *yy* of Fig. 1; Fig. 4, elevation of clamp or frame for holding matches.

The first part of my invention consists in the employment of a loose box or frame in the hopper in which the match-splints are placed to be fed into the machine, said loose box or frame being set into the hopper loosely, so that it will move up and down in the hopper, to avoid cutting and jamming match-splints, by the reciprocating movement of the hopper. This loose box or frame has a series of cross blades or divisions at or near the bottom, a scraper on the front lower edge, and a follower or flat weight to keep the match-splints down, the operation of the whole being to scrape the match-splints placed within the box when in the hopper over a grooved bed, so as to fill the grooves of the bed with match-splints.

The second part of my invention consists in dividing the grooved bed in two parts, the front part being hinged to the rear part and secured in place by a button or other suitable device when the machine is in action, the division and joint being made for the purpose of letting down the front part of the grooved bed to remove broken splints and slivers which obstruct the action of the machine.

The third part of my invention applies to match-splints of what is called "double length"—that is, match-splints of twice the length of the match. Such splints are now generally used, being dipped at both ends while in the frame, and afterward, when dried, cut in two. In framing such matches in clamp-frames by sliding plungers and a grooved bed, owing to their length, they are liable to become disarranged in the clamps when pushed out beyond the end of the grooved bed, which they have

to be in order to let them pass down with the clamp-frame. This part of my invention consists in a series of guides projecting from the grooved bed forward, said guides being formed from the metal of the grooved bed by slotting out the grooves in front. These guides keep the match-splints straight while the upper member of each division of the clamp-frame is being applied and while said frame with the framed splints is being lowered to receive a new layer of splints.

The fourth part of my invention consists in a combination of the frame of plungers with the match-splint-frame holder, whereby the latter is moved downward the distance of the thickness of the members of the splint-frame at each back stroke of the plunger-frame after it has pushed the match-splints forward into the splint-frame.

But in order to more particularly describe my improvements, I will refer to the drawings by letters of reference.

I construct my machine in a case or cabinet, *a*, inclosed at the sides and back and having a lid, *a'*, which may be thrown back, as shown in the drawings, to get at the plungers.

The grooved bed, which separates the match-splints and guides them as they are thrown forward to the frames, consists of a fixed part, *b*, firmly secured to the side frame, and a swinging part, *b'*, hinged to the fixed part by hinges, so as to swing downward away from the hopper and cross-bar, in order to remove slivers, broken splints, or other obstructions. This hinged part is kept in place on a level with the fixed part by a suitable dog or button, *b²*, on the fixed part, the handle or crank of which, *b³*, for convenience, I place on the upper side of the bed. When fixed in position to operate the grooves in both parts coincide.

The front part of the hinged portion of the grooved bed is slotted with parallel slots *b⁴*, coinciding with the grooves, the sides of the slots forming guides for the splints while passing into the frames, and also (the slots being of the depth of the grooved bed) serving as guides to keep the splints in place while the upper member of each clamp of the frame is put on and the frame lowered.

Two bars, *c c'*, lie close to and across the grooves of the grooved bed, being secured at

their ends firmly thereto. The rear bar, *c*, keeps the plungers in the grooves and the rear ends of the splints in line. The front bar, *c'*, keeps down the splints in the grooves when they are being thrown forward to the frame and keeps back the rest of the splints in the hopper. The bars are placed a little farther apart than the length of the splints.

The hopper *d* is placed immediately over and close to the cross-bars, and is supported by and slides back and forth across the grooved bed on guides *d'* *d''*, secured to the side frames. Within the hopper is placed loosely a box or frame, *e*, which may be made of sheet metal. The bottom of this loose frame or box is open and has across it a series of blades or scrapers, *e'*, to scrape or draw the splints into the grooves of the bed. There is also a scraper or blade, *e''*, on the front lower edge of the loose box to keep back the splints in the box from following those in the grooves.

A follower or flat weight, *e³*, lies on the splints within the loose frame to keep them down, so as to be drawn or scraped within the grooves.

The hopper, with its inside loose frame and splints, is drawn back and forth over the grooved bed to fill the grooves with splints by means of a bent lever, *f*, and reacting spring *g*, the bent lever being connected by a link, *f'*, from one of its arms to the hopper, and also by a link, *f''*, to the treadle *f³*.

The splints in the grooves of the grooved bed are projected therefrom into a match-splint frame of clamps, *h*, by a series of plungers, *i*, which fit the grooves and are attached to the back bar of a sliding frame, *j*, which slides in guides on the side frame, the front bar, *j'*, of the sliding frame being in front of the machine for the purpose of grasping it by the hands to move the frame back and forth.

The match-splint frame *h* is constructed as usual. It is supported by and rests on a sliding frame, *k*, which slides up and down in the front part of the machine in the guides *k'*. The weight of this sliding frame is supported by the counterbalance-weights *k²* on each side of the machine, which are connected to the sliding frame by cords *k³*, running over pulleys *k⁴* *k⁵*. The weights should be heavy enough to lift the sliding frame and the splint-clamp frame to the extent of the upward motion of the sliding frame whenever released from the mechanism used for feeding the frame downward and holding it in position to receive layer after layer of splints until the splint-frame is filled with splints.

The mechanism for feeding the frame downward and holding it in position for receiving the splints is as follows: Upon the sliding frame *k* are placed two racks, *m*, one on each side of the frame. A dog or catch, *n*, actuated by a spring, *n'*, and pivoted on a pin, *n''*, screwed into the side frame, takes into the rack and prevents the weights from lifting the frame, (unless when it is released from the

rack, as hereinafter explained,) but does not interfere with the sliding frame being pushed downward, when required to put in succeeding layers of splints, by means of pawls *p*, attached to levers *p'*, which are pivoted on fulcrum-pins *p²*, screwed into the side frame of the machine.

The arrangement of the pawls and levers and holding-dog is the same on both sides of the machine, a view of one side being shown in Fig. 2.

The levers *p'*, which carry the pawls *p*, are connected by adjustable links to cranks *p³* on each end of the rock-shaft *g*, which extends across the machine at the rear, just below the plunger-frame, and is supported in bearings *q'* *q²*. At the middle of the said rock-shaft is an arm, *r*, which extends upward to the rear of the plunger-frame, so that the plunger-frame, as it approaches the termination of its back movement, comes in contact with the arm, thereby giving motion to the rock-shaft levers and pawls to feed down the sliding frame the required distance.

The pawl-levers *p'* are reacted by the springs *s*, the range of motion being limited by a stop, *s'*, being placed under the levers.

When the splint-frame is filled with splints the upper bar of the clamp is put on, the screws tightened, and then it is ready to be lifted out of the machine and replaced by an empty one.

The dogs and pawls may be released by hand in order to raise the sliding frame; but for convenience I prefer to release them by mechanical means, as follows:

A crank-handle, *t*, is placed at the side of the machine, attached to a rocking cam-shaft, *u*, which passes across the machine. This shaft carries short arms or cams *u'*, which, when the shaft is turned a little by pressing on the crank-handle, push back the pawls and dogs, thereby releasing the sliding frame and permitting it to be drawn upward by the weights. The rock-shaft *u* also carries arms *u²*, to which springs *u³* are connected to throw back the rock-shaft when relieved from the pressure of the hand.

The rock-shaft is not shown in the drawings, except in section, Fig. 2, it not being deemed necessary, as the parts are the same on both sides of the machine.

The pawls *p* are connected with the levers *p'* by a pin, *p⁴*, on which they swing, and being kept against the racks *m* by springs *p⁵*, attached to the levers *p'* and bearing on the pawls, they yield readily to the pressure of the releasing-cam *t* when it is applied.

What I claim as my invention and improvements in match-splint-framing machines is—

1. In combination with the grooved bed and hopper, the loose hopper box or frame, constructed and operating substantially as described.

2. The construction of the grooved bed in two parts, the front part being hinged to the rear fixed part, for the purpose of being swung

down below the plane of the fixed part when required to remove broken splints, slivers, or other obstructions, substantially as described.

3. In combination with the grooved bed, the guides or slots in front of the grooved bed, substantially as described.

4. In combination with the plunger-frame and the front sliding frame which supports the splint-frame, the rock-shaft and system of

pawls and levers whereby the down-feed motion of the sliding frame is communicated thereto by the back motion of the plunger-frame.

JACOB BENTZ.
